C. W. SMITH.

Electric Gas Lighter.

No. 21,781.

Patented Oct. 12, 1858.

UNITED STATES PATENT OFFICE.

C. W. SMITH, OF EVANS, NEW YORK.

IMPROVED METHOD OF LIGHTING STREET-LAMPS BY ELECTRICITY.

Specification forming part of Letters Patent No. **21,781**, dated October 12, 1858.

To all whom it may concern:

Be it known that I, CHARLES W. SMITH, of the town of Evans, in the county of Erie and State of New York, have invented a new and Improved Mode of Lighting Gas by Electricity; and I do hereby declare that the following is a full and exact description thereof, reference being had to the accompanying drawings, and to the letters of reference marked thereon.

The nature of my invention consists, first, in the combination and arrangement of a circuit-changer with different circuits of conducting-wires, in which circuits are included devices for lighting street-lamps by electricity, in such a manner that a portion of the street-lamps of a city may be lighted at a time, thus obviating the necessity of employing a battery of inconvenient and expensive size; secondly, in the combination of conducting-wires with such circuit-changer or changers in such a manner that the latter may be operated by means of electricity at a part of the city remote from the operator; thirdly, in arranging the parts of a gas-lighter in such a manner that they will be more compact and less liable to get displaced than heretofore, as will be described.

To enable others skilled in the art to make and use my invention, I will proceed to describe its construction and operation.

Figure 1 is a plan view of the apparatus for lighting street-lamps.

At B is seen the circuit-changer of the central station, which is operated by hand. The electric current starting from the battery A proceeds along the conducting-wire to the central pivot of the circuit-changer; thence through the radial arm C to the metallic segments D D' E E', &c.; thence through the conducting-wires which radiate to different secondary or district stations. It will be observed that two of these wires proceed to each district station. One of these wires, as D, is used to turn around the district circuit-changer, so as to make a connection between the wire D' and the different segments of the changer, which communicate also through radial wires with the different circuits of wires in which are included the lamps, one of which circuits is represented on a reduced scale at R. The lamps in this cir-

cuit are then lighted by means of the wire D', and the current being again transmitted through D converts the soft iron I into a magnet, which attracts the armature K, actuates the lever L, the pawl M, the ratchet N, and thus moves around the radial arm O until, by a succession of strokes, it is brought in contact with the segment communicating with another circuit. In this manner the different districts and the different sections of each district can be lighted in rapid succession by a battery which would prove wholly inadequate to light them all at once. So soon as the lamps are all lighted, the conducting-wires may be put in connection with the electrograph P P, and thus be used for transmitting signals until the lamps are to be extinguished, when the same operation is to be repeated.

I have also made some improvements in the construction of the gas-lighters which are operated as described above.

I place the temporary magnet A, Fig. 4, immediately above the supply-clock B instead of beneath, as has been done heretofore in all cases, I believe, when a U-magnet has been used, and support it there by means of the brass plate C, slips of which are cut and bent so as to form a fulcrum for the lever D and a guide to the pawl E. The devices are thus rendered extremely simple and compact, and it becomes impossible for them to get displaced.

What I claim as my invention, and desire to secure by Letters Patent, is—

1. The combination and arrangement of a circuit-changer with different circuits of conducting-wires, in which are included a number of street-lamps, in such a manner that the lamps in one circuit only may be lighted simultaneously by means of the battery-current.

2. The combination of conducting-wires with devices for operating, by electricity, such a circuit-changer at a station remote from the operator.

3. The arrangement of the magnet A, the brass plate C, the lever D, and the pawl E, substantially as and for the purposes described.

CHARLES W. SMITH.
